Attn's

UNITED STATES PATENT OFFICE.

SAMUEL NORMAN BURGESS, OF LONDON, ENGLAND.

DESIGN FOR A WRISTLET WATCH.

Application filed January 3, 1928, Serial No. 24,730, and in Great Britain September 22, 1927. Term of patent 7 years.

To all whom it may concern:

Be it known that I, SAMUEL NORMAN BURGESS, a subject of the King of England, residing at 7 Hatton Garden, London, E. C. 1, England, have invented a new, original, and ornamental Design for a Wristlet Watch, of which the following is a specification, reference being had to the accompanying drawing, forming part thereof.

Figure 1 discloses a front view and Figure 2 a side view of the wristlet watch illustrating my new design.

I claim—

The ornamental design for a wristlet watch, as shown.

SAMUEL NORMAN BURGESS.
